UNITED STATES PATENT OFFICE.

FREDERICK N. PEASE AND MILTON E. McDONNELL, OF ALTOONA, PENNSYLVANIA.

DETERGENT FOR CLEANING AND POLISHING PURPOSES.

1,052,952.

Specification of Letters Patent. Patented Feb. 11, 1913.

No Drawing.

Application filed April 30, 1912. Serial No. 894,266.

To all whom it may concern:

Be it known that we, FREDERICK N. PEASE and MILTON E. McDONNELL, citizens of the United States, residing at Altoona, in the county of Blair and State of Pennsylvania, have invented certain new and useful Improvements in Detergents for Cleaning and Polishing Purposes; and we do hereby declare the following to be a full, clear, and 10 exact description of the invention, such as will enable others skilled in the art to which it appertains to make and use the same.

This invention relates to a detergent for cleansing and polishing purposes in general, but especially adapted for cleaning and polishing varnished and polished surfaces on coaches, vehicles, etc.

It has for its object to produce a composition of matter for these purposes which will 20 be efficient in action, comparatively inexpensive to manufacture, and will leave a highly finished surface with an appearance and odor suggesting a clean and freshly varnished article.

25 To these ends, the invention consists in the novel combinations of ingredients more fully hereinafter disclosed and particularly pointed out in the claims.

In carrying out our invention, we preferably dissolve a fatty acid, such as stearic acid in a neutral mineral oil, such as paraffin, or kerosene, or both, and also preferably apply some heat to aid in the solution when a solid acid is used. We next preferably 30 add a caustic alkali, such as caustic soda, in the form of a water solution from which all carbonates have been preferably removed. Care should be taken to add just enough alkali to neutralize the acid present and to 35 render the subsequent emulsion neutral. During the addition of the said alkali, and during all the subsequent additions, the mixture is preferably suitably agitated, as by a mechanical means, in order to form an 40 emulsion and to prevent the water and the soap that is formed from separating from the mineral oil. Should this emulsion just disclosed be allowed to stand, the said soap and water will finally separate out and 45 destroy the emulsion. In order to prevent this, and to hold the emulsion permanently, we next form a colloidal mixture of a suitable gum, such as gum tragacanth and water, and by a suitable agitation thor- 50oughly incorporate this colloidal mixture with the above emulsion. This compound 55

or emulsion thus produced will hold its form indefinitely when the ingredients are properly proportioned, and it is found to be a very useful detergent without any additions for many purposes. However, for most purposes, in order to save labor and to increase the rapidity of the action, we add suitable additions of a finely divided abradant, such as silez, tripoli, etc., and thoroughly incorporate the same into the above emulsion. The abradant containing emulsion thus produced will hold its form and constitute an efficient cleansing and polishing agent. However, notwithstanding the 60 fact that the gum tragacanth will prevent the soap and water from separating from the mineral oil, and will also prevent the finely divided abradant from settling to the bottom, yet the soap when first formed tends 65 to go into a more or less gelatinous mass, and later appears to assume a more or less solid crystalline condition. After this crystalline form has appeared, we again thoroughly agitate the mass, so as to break up 70 the soap and to form a paste. Later, upon standing, although the soap may tend again to assume a solid form, yet it never forms more than a thick semi-solid paste, which may be easily dipped out of the container 75 and applied to the surface to be cleaned and polished. In fact, the paste-like form is easier of application than would be a liquid form.

In practice we prefer to add gum ammoniac to the gum tragacanth in making the above colloidal mixture, which materially aids in maintaining the emulsion, and we believe it also aids in imparting a luster to the polished surface. It certainly imparts a 80 pleasant odor of a freshly varnished surface to the parts cleaned. The abradant, of course, can be added either before or after the colloidal mixture is added. When stearic acid is used, we also preferably add 85 some red oil, in order to prevent the soap from being hard and stringy, but of course any other suitable soap may be formed, or of course a ready made commercial soap may be suitably incorporated with the mineral oil. When kerosene is used, we also prefer to employ some paraffin oil for the purpose of giving more body to the vehicle; but, of course, a large number of other oils 90 could be used.

105 The proportions of the above ingredients may be widely varied, but we have found the 110

following proportions to give the most excellent results, and prefer to employ the same:—Paraffin oil 197 lbs., kerosene 197 lbs., red oil 13 lbs., stearic acid 9 lbs., caustic soda 11 ozs., water 141 lbs., silex 72 lbs., tripoli 36 lbs., gum tragacanth 8 oz., gum ammoniac 8 oz.

When mixed as above, and the above proportions, for example, are followed, there is 10 produced a pale yellowish pasty mass, which when applied to the varnished surfaces of railroad cars, automobiles, etc., is found to clean the same efficiently and quickly, without injury to the varnish, and to leave a 15 pleasant odor of a freshly varnished surface behind.

It is obvious that those skilled in the art may, as above indicated, vary the combinations as well as the proportions of parts 20 without departing from the spirit of our invention, and therefore we do not wish to be limited to the above disclosure, except as may be required by the claims.

What we claim is:—

25 1. A composition of matter adapted for cleaning purposes, consisting of an emulsion

containing a neutral stearin soap, paraffin oil, finely divided tripoli, gum tragacanth, and water, substantially as described.

2. A composition of matter adapted for 30 cleaning purposes, consisting of an emulsion containing a neutral stearin soap, paraffin oil, finely divided tripoli, gum tragacanth, water, and gum ammoniac, substantially as described. 35

3. A composition of matter adapted for cleaning purposes, consisting of an emulsion containing the following ingredients in substantially the following proportions:—paraffin oil 197 lbs., kerosene 197 lbs., red oil 13 40 lbs., stearic acid 9 lbs., caustic soda 11 ozs., water 141 lbs., silex 72 lbs., tripoli 36 lbs., gum tragacanth 8 oz., gum ammoniac 8 oz., substantially as described.

In testimony whereof, we affix our signatures, in presence of two witnesses. 45

FREDERICK N. PEASE.
MILTON E. McDONNELL.
